OTHER PUBLICATIONS

Two photographs of belt with non-twisting D-rings (May 21, 2014).

Primary Examiner — Catheri Oliver-Garcia*(74) Attorney, Agent, or Firm* — Duane Morris LLP; J. Rodman Steele, Jr.; Gregory M. Lefkowitz(57) **CLAIM**

The ornamental design for a tool belt with non-twisting D-rings, as shown and described.

DESCRIPTION

FIG. 1 is a front, perspective view of my ornamental design; FIG. 2 is a front view of the ornamental design of FIG. 1; FIG. 3 is a rear view of the ornamental design of FIG. 1; FIG. 4 is a top view of the ornamental design of FIG. 1; FIG. 5 is a bottom view of the ornamental design of FIG. 1; FIG. 6 is a right side view of the ornamental design of FIG. 1; and, FIG. 7 is a left side view of the ornamental design of FIG. 1. The broken lines are included for purposes of illustrating environment and form no part of the claimed design.
